Ebenezer T. Starr, of New York, N.Y.
Letters Patent No. 7760, dated May 12, 1863.

The schedule referred to in these Letters Patent and making part of the same.
To all whom it may concern.

Be it known that I, E. T. Starr, of the City, County, and State of New York, have invented or produced a new and original design for a Skate; and I do hereby declare that the following is a full, clear and exact description of the same, reference being had to the

286

Dec 1768

accompanying drawings making a part of this specification in which,
Figure 1. is a side view of a skate constructed
according to my design.

Figure 2. a transverse section of the same,
taken in the line xx. xx. Figure 1.

Similar letters of reference indicate corresponding parts in the two figures.

A represents the sole plate or foot stand
of the skate which has its heel or back part a, somewhat depressed or
sunk down, as shown in clearly in Figure 1. The sole plate has three run-
ners b. b. b. attached to it which form ports or knees into which the run-
ner B is secured. This runner is of the usual rocker form and has a
projection c. at each side of its lower part which forms a flat head ex-
tending the whole length of the runner, see Figure 1.

The projection c gives a finished or
neat appearance to the runner of the skate, and the projection c of
the runner in connection with the sole plate or foot stand A form
a new and original design for a skate.

What I claim as new and desire
to receive by Letters patent, is

The configuration of the runner B. and
sole plate A as herein described to form a new and original design
for a skate.
